(57) **CLAIM**

The ornamental design for a protective lid with scrollable cover and a removable element, as shown and described.

DESCRIPTION

FIG. 1 is a top perspective view of the protective lid with scrollable cover and a removable element.

FIG. 2 is a bottom perspective view of the protective lid with scrollable cover and a removable element.

FIG. 3 is a top perspective view of the protective lid with scrollable cover and the removable element removed.

FIG. 4 is a top perspective view of the protective lid with scrollable cover and a removable element in use.

FIG. 5 is a bottom perspective view of the protective lid with scrollable cover and a removable element in use.

FIG. 6 is a top projected view of the protective lid with scrollable cover and a removable element illustrating its assembly.

FIG. 7 is a bottom projected view of the protective lid with scrollable cover and a removable element illustrating its assembly.

FIG. 8 is a top plan view of the protective lid with scrollable cover and a removable element.

FIG. 9 is a bottom plan view of the protective lid with scrollable cover and a removable element.

FIG. 10 is a side view of the protective lid with scrollable cover and a removable element.

FIG. 11 is a front view of the protective lid with scrollable cover and a removable element; and,

FIG. 12 is a rear view of the protective lid with scrollable cover and a removable element.

The broken lines in FIGS. 4 and 5 depict a cup with the protective lid with scrollable cover and a removable element in use showing the environment forming no part of the claimed design.
